Karl Nacker,

INVENTOR,

BY Dodson & Roe

His ATTORNEYS.

UNITED STATES PATENT OFFICE.

KARL NACKE, OF BROOKLYN, NEW YORK.

DESIGN FOR A HUSK FOR WALL PLATES.

Application filed October 19, 1922. Serial No. 4,023. Term of patent 3½ years.

To all whom it may concern:

Be it known that I, KARL NACKE, a citizen of the United States, and residing at Brooklyn, in the county of Kings and State of New York, have invented a new, original, and ornamental Design for Husk for Wall Plates, of which the following is a specification, reference being had to the accompanying drawing, forming a part thereof.

Fig. 1 is a front view of my improved husk for wall plates;

Fig. 2 is a side view showing the contour;

Fig. 3 is a side view showing the ornamentation;

Fig. 4 is a back view showing the contour.

I claim—

The ornamental design for a husk for wall plates as shown.

KARL NACKE.
